Samuel E. Hohulin, Lexington, and Harold W. Schaefer, Bloomington, Ill., assignors to National Union Electric Corporation, Stamford, Conn.

Filed Oct. 12, 1970, Ser. No. 25,441

Term of patent 14 years

Int. Cl. D15—05

U.S. Cl. D49—14.1

FIGS. 1 and 2 are perspective views of a suction cleaner showing our new design, as seen from the opposite ends thereof;

FIGS. 3 and 4 are top and bottom plan views, respectively, of the cleaner shown in FIGS. 1 and 2;

FIG. 5 is a side view;

FIGS. 6 and 7 are end views;

FIG. 8 is a perspective view of another suction cleaner embodying our new design; and

FIG. 9 is a perspective view of still another suction cleaner embodying our new design.

The side of the cleaner opposite from the side thereof shown in FIG. 5, has the same ornamental appearance as the side shown in FIG. 5.

We claim:

The ornamental design for a suction cleaner, substantially as shown and described.
